UNITED STATES PATENT OFFICE.

HORACE JOSEPH MIER, OF RUTHERFORD, NEW JERSEY.

DESIGN FOR A MUSTACHE-GUARD.

SPECIFICATION forming part of Design No. 34,311, dated April 2, 1901.

Application filed March 1, 1901. Serial No. 49,515. Term of patent 7 years.

To all whom it may concern:

Be it known that I, HORACE JOSEPH MIER, a citizen of the United States, residing at Rutherford, county of Bergen, and State of New Jersey, have invented and produced a new and original Design for Mustache-Guards, of which the following is a specification, reference being had to the accompanying drawings, forming part thereof, in which—

10 Figure 1 is a plan view of a mustache-guard, showing my new design; and Fig. 2, a transverse section thereof on the line 2 2.

15 My newly-designed mustache-guard is adapted to be placed upon a cup, bowl, or similar vessel, and the leading or material feature thereof consists of the annular body portion *a*, having a depending annular flange or rim *b* and an inwardly-directed annular

flange or rim *c*, which is also slightly depressed and across one side of which is a segmental strip *d*, forming an elliptical space *e*, the segmental strip *d* being also slightly depressed, as clearly shown in the drawings.

Having fully described my invention, what I claim as new, and desire to secure by Letters 25 Patent, is—

The design for a mustache-guard, as herein shown and described.

In testimony that I claim the foregoing as my invention I have signed my name, in presence of the subscribing witnesses, this 27th day of February, 1901.

HORACE JOSEPH MIER.

Witnesses:

F. A. STEWART,
L. R. BAYER.
